UNITED STATES PATENT OFFICE.

JENS A. PAASCHE, OF CHICAGO, ILLINOIS.

PNEUMATIC PAINT-BRUSH.

1,104,217.

Specification of Letters Patent.

Patented July 21, 1914.

Application filed April 11, 1910. Serial No. 554,669.

To all whom it may concern:

Be it known that I, JENS A. PAASCHE, a citizen of the United States, residing at Chicago, in the county of Cook and State 5 of Illinois, have invented certain new and useful Improvements in Pneumatic Paint-Brushes, of which the following is a specification.

This invention relates to a pneumatic brush which is especially adapted for use with paint of heavier consistency than that used with the common air brush, such as house paints, varnishes, enamels, etc.; although the brush is not limited to such use, 15 since it operates satisfactorily with any liquid coloring matter.

One of the objects of the invention is to provide improved means for controlling the air supply.

Another object is to improve the construction of the color-discharge means.

A further object is to provide a novel means for supporting the brush.

Another object is to provide means for 25 agitating the contents of the paint container.

Another object is to provide an adjustable connection between the forward section and the remainder of the body, so that the color discharge means may be positioned at different 30 angles upon the body.

Other objects and advantages will appear from the following detailed description.

In the accompanying drawings Figure 1 is a side elevation of a pneumatic paint brush embodying the features of my invention. Fig. 2 is a vertical central section through the brush. Fig. 3 is an enlarged section of the rear part of the brush taken upon the same plane as Fig. 2. Fig. 4 is 40 a section on line 4 4 of Fig. 3. Fig. 5 is an enlarged fragmental section through the air and color-discharge nozzles. Fig. 6 is an enlarged section on line 6 6 of Fig. 2. Figs. 7 and 8 are fragmental detail views 45 of the paint-feeding tube or needle. Fig. 9 is a fragmental side elevation illustrating the manner of using a pigment cup instead of the bottle shown in Fig. 1.

In the embodiment of the invention which 50 I have selected for the purpose of illustration, the body of the brush comprises a barrel 1 having a handle 2 secured thereto, the brush being arranged to be held by said handle in the manner of a pistol. The forward end 3 of the body is tapering, as shown, 55 and in the present form is separate from

the barrel 1, said forward end having a contracted exteriorly-threaded portion 4 which is arranged to engage the interior threads in one end of the barrel 1. A lock nut 5 60 upon said contracted portion locks the said parts together. Projecting downwardly from the forward portion of the body is a lug 6 having an opening 7 therein, in which opening is adjustably mounted a sleeve 8. 65

The bottle or other container 9 for the paint may be of any suitable construction. A tube 10 extends through the cover 11 for the bottle to a point near the bottom of the bottle and preferably near the forward side 70 of the bottle so that when the brush is inclined downwardly the contents of the bottle may be practically completely discharged. The tube 10 is arranged to fit within the rear end of the sleeve 8. A set 75 screw 12 screw-threaded in the lug 6, is adapted to lock the sleeve 8 against movement. 13 is a set screw for locking the tube 10 in the sleeve 8.

Fixed in the forward end of the sleeve 8 80 is a tube or needle 14. The forward end of the tube 14 is tapered as at 15, the opening through said tube terminating at 14^a upon the side of said tapered portion 15 as shown in Figs. 7 and 8. Fitting tightly 85 about the tube 14, and slidable longitudinally thereupon, is a nozzle 16, the forward end of said nozzle being interiorly tapered to fit the tapered end 15 of the tube 14 and thereby control the discharge of paint 90 from said tube. It will be seen from Figs. 2 and 7 that the tapered portion 15 is relatively short or blunt, so that the outlet 14^a for the paint is located close to the orifice of the nozzle 16. The rear end of the nozzle 16 has a screw-thread connection with the sleeve 8, so that the rotation of the nozzle will move the same longitudinally along the tube 14 and will thus permit more or less paint to be discharged, according to the size 95 of the opening between the tapered end 15 of the tube and the inner wall of the nozzle tip. 17 is a knurled flange on the nozzle 16 by which said nozzle may be rotated.

Upon the forward end of the tapered portion 3 of the body is an air nozzle 18 having a flaring guard flange 19 at its forward end. An opening 20 is provided in the flange 19 through which opening the forward end of the paint nozzle 16 extends so that the current of air issuing from the air nozzle will 110 draw the paint through the nozzle 16 and

atomize it. The guard flange 19 protects the tip of the nozzle 16 and tube 14 against injury.

The rear end of the barrel 1 is closed by a head 21 which carries the pressure fluid valve mechanism. Said head has an exteriorly-screw-threaded portion 22 which is turned into the interiorly-threaded end of the barrel. In the rear end of the head 21 is formed a recess 23. A threaded opening 24 extends centrally through the head from its inner face to the center of the recess 23. A member 25 is arranged to extend into the recess 23 of the head and close said recess, said member having at its forward end a threaded stem 26 which is turned in the opening 24 in the head 21, the stem 26, in this instance, extending entirely through the head. The inner end of the member 25 is somewhat reduced in diameter, as at 27, thus forming an annular chamber 28 between said inner end and the wall of the recess 23.

A passage 29 extends centrally through the member 25 and is continued in a somewhat reduced diameter through the stem 26. An annular shoulder 30 formed in the wall of said passage provides a valve seat against which a valve member 31, having a stem 32, is adapted to seat, and thereby control the flow of pressure fluid through said passage. The valve member 31 is held seated by means of a coiled spring 33 bearing at one end upon said valve member, and at its other end against a hollow plug 34 threaded in the outer end of the passage 29 in the member 25. A valve-operating stem 35 fits slidably within the forward end of the passage 29 in the stem 26. Screw threaded upon the rear end of the member 25 is a nipple 36 adapted to have a suitable pressure fluid conductor, such as a rubber hose, attached thereto. A port 37 connects the passage 29 in front of the valve member 31 with the annular chamber 28. Another port 38 extends 45 through the head 21 from the annular chamber 28 to the inner face of said head 21. A pipe 39 is threaded at one end in the port 38 and at its other end has, in this instance, a screw-thread connection with the air nozzle 18. Said pipe is adapted to convey pressure fluid from the port 38 to the air nozzle 18.

The means for unseating the valve 31 to permit the passage of air to the air nozzle 18 comprises, in this instance, a trigger lever 40 extending into an opening 41 in the lower side of the barrel 1, and pivotally mounted at its upper end by means of a tapered pin 42 extending through the walls of the barrel 60 and through said end of the lever. It will be understood that the lever is adapted to be operated by the index finger when the operator's hand is gripping the handle 2. 40^a is a set screw forming an adjustable stop to limit the opening movement of the lever 40.

A link 43 is pivotally connected at one end with the trigger lever 40 by means of a pivot pin 44 and at its other end is pivoted to the forward end of the valve operating stem 35.

In applying certain paints, as, for instance, bronzes, it is necessary to agitate the paint to prevent settling of the pigment. I, therefore, provide means for discharging compressed air into the bottles, one example 75 of which means will next be described.

A tube 45, connected at one end in a suitable manner with the annular chamber 28, is supported near its other end by a suitable loop or eye upon the barrel 1, and is extended to a point near the bottle 9. 46 is a tube attached to the cap 11 of the bottle and extending to a point near the bottom of the bottle. The tubes 45 and 46 may be detachably connected by a section of flexible tubing 85 47. 48 (Fig. 4) is a needle valve for regulating the flow of air through the tube 45.

In order that the brush may be set in an upright position upon a table or other support, I provide a rod 49 which is vertically 90 slidable in the handle 2 and may be fixed in adjusted position by a set screw 50. In practice, the rod 49 is fixed in such position that its lower end is in the same horizontal plane as the bottom of the bottle 9, so that when 95 the brush is placed upon a table it will be supported by the bottle and the rod 49.

The reason for rotatably connecting the forward section 3 to the barrel 1 is to permit of substituting a pigment cup 50 for the bottle 9 (see Fig. 9). When it is desired to use such a cup instead of a bottle, the section 3 is turned so that the parts 6 and 16 are in the same horizontal plane with the section 3, and the latter is secured in such position by means of the lock nut 5. A cup 50 of the usual form having a tubular attaching stem 51 may now be connected to the tubular needle 14 by inserting the end of said stem in the sleeve 8. It will be understood that a less powerful air current will be needed to draw paint from a cup supported at approximately the same level as the air current than from a container located below the air current.

In operation, when the paint nozzle 16 has been adjusted on the tube 14 to the position to permit the flow of the desired amount of paint, the trigger lever 40 is moved rearwardly to unseat the valve 31. Air under 120 pressure now travels through the passage 29, port 37, chamber 28, port 38, and through the pipe 39 to the air nozzle 18 where the air draws paint from the container 9, disintegrates the paint and carries it against the 125 article to be coated.

It will be observed that the outlet for the paint is relatively large, so that heavy finishes such as ordinary house paint, japans, lacquers, bronze paints, etc., can be applied 130

by means of the brush. In practice, it has been found that paints which are not of smooth or even consistency, *i. e.*, having lumps or sediment therein, can be successfully used with the tool herein shown. Furthermore, the paint outlet 14^a of the tube 14 is relatively near to the outlet or orifice of the nozzle 16, said paint outlet being located in the side of the short or blunt conical end 15 of the tube 14. The paint therefore does not need to travel far from the outlet 14^a before reaching the orifice of the nozzle 16, and hence any color remaining in the nozzle when the operator shuts the air valve may readily flow back through the outlet 14^a and into the tube 14. Therefore, none of the paint remains in the nozzle to eventually work back into the rear part of the nozzle and into the screw thread connection between the nozzle and the sleeve 8. I regard the constructional features just referred to as being of great practical importance.

I am aware that various changes from the embodiment herein shown may be made without departing from the invention; therefore, I do not limit myself to the exact construction herein shown and described.

Certain features of the device herein disclosed are claimed broadly in my co-pending application Serial No. 492,013 filed April 24, 1909.

I claim as my invention:

1. In a pneumatic paint brush, in combination, air-discharge means; and color-discharge means comprising a sleeve, a tube secured to said sleeve, the forward end of said tube being tapered and the opening therein terminating upon the surface of said tapered portion, and a nozzle fitting upon the forward end of said tube and being internally tapered to fit the forward tapered end of said tube, said nozzle having a connection with said sleeve, whereby the nozzle may be moved longitudinally of said tube to control the discharge of color.

2. In a pneumatic paint brush, in combination, a body; air-discharge means carried by said body; a lug on said body having an opening therein; a sleeve mounted in said opening; a tube fixed in the forward end of said sleeve, the forward end of said tube being tapered and the opening therein terminating upon the surface of said tapered portion, and a nozzle fitting upon said tube and being internally tapered to fit the forward tapered end of said tube, said nozzle having a screw-thread connection with said sleeve, whereby the nozzle may be moved longitudinally of said tube to control the discharge of color.

3. In a pneumatic paint brush, in combination, pressure-fluid-discharge means; and paint-discharge means comprising a tube adapted to convey the paint, the forward

end of said tube being tapered bluntly, the opening in said tube being relatively large and terminating upon the face of said tapered portion, and a nozzle fitting tightly upon said tube and being interiorly tapered 70 to fit the forward tapered end of said tube, said nozzle and said tube being slidable with relation to each other to control the discharge of paint.

4. In a pneumatic paint brush, in combination, a body comprising a barrel; color-discharge means at the forward end of the body; an air nozzle adjacent to said color discharge means; a head closing the rear end of said barrel, said head having a recess in its outer face and having a port connecting said recess with the inner face of said head; a pipe in said barrel connecting the inner end of said port with said air nozzle; a member closing said recess, said member having an air passage therein communicating at its inner end with said recess; a valve in said passage for controlling the flow of air therethrough; a valve-operating stem slidable in said member and extending into the rear end of said barrel; a finger lever extending into and pivoted in said barrel; and a link within said barrel connecting said finger lever with the inner end of said valve-operating stem. 95

5. In a pneumatic paint brush, in combination, a body comprising a barrel, color discharge means at the forward end of the body, an air nozzle adjacent to said color discharge means; a head closing the rear end 100 of said barrel, said head having a recess in its outer face and having a central screw threaded opening extending from said recess to the inner side of said head, said head having a port connecting said recess with the inner face of said head, a pipe within said barrel connecting the inner end of said port with said air nozzle, a member closing the recess in said head and having a stem threaded in said central opening, said member having a passage therein communicating at its inner end with said recess, a valve in said passage for controlling the flow of air therethrough, a valve operating stem 110 slidable in the first mentioned stem and extending into the rear end of said barrel, and a finger lever adapted to slide said stem to open said valve. 115

6. In a pneumatic paint brush, in combination, a body, a forward section adjustably connected therewith and having a lug thereon, color discharge means carried by said lug, said forward section being movable into position with said lug extending downwardly for attachment to a paint bottle or 120 extending laterally for attachment with a pigment cup, and means for locking said section to said body in either of said positions. 125

7. In a pneumatic paint brush, in combi- 130

nation, a body comprising a barrel; a forward section having a screw-thread connection with said barrel; paint-discharge means supported by said forward section, said section being rotatable to change the position of said paint-discharge means with reference to said barrel, whereby either a paint bottle or an open paint cup may be used in connection with said paint discharge means and a jam nut for locking said section to said barrel in adjusted positions.

8. In a pneumatic paint brush, in combination, an elongated body, an air nozzle at the forward end of said body, a downwardly projecting lug adjacent to the forward end of said body, paint discharge means mounted in said lug, a paint bottle depending from said lug, a downwardly projecting handle secured to the rear portion of said body, by which handle the device may be held in the hand like a pistol, a head carried at the rear end of said body and having a recess therein, a valve controlling the flow of pressure fluid into said recess, a pipe within said body connecting said recess with the air nozzle, a second pipe leading from said recess to said paint bottle, and a downwardly projecting trigger lever mounted in the body forwardly of said handle and operatively connected with said valve.

9. A pneumatic paint brush comprising a tube tapered bluntly at one end and having a relatively large longitudinal opening

adapted to convey paint, said opening terminating upon the tapered surface of said tube, and a nozzle surrounding said tube and interiorly tapered to fit against the tapered end of said tube to control a discharge of paint therefrom.

10. A pneumatic paint brush comprising a tubular paint conductor having a tapered forward end and having a longitudinal opening terminating on the tapered surface, and a nozzle surrounding said conductor and being interiorly tapered to fit against said forward end and thus close the end of said opening, said nozzle having a screw thread connection with said conductor.

11. In a pneumatic paint brush, air-discharge means, and paint discharge means comprising a sleeve having a passage therethrough, a color receptacle having a conduit extending into one end of said passage, a tube secured to said sleeve and communicating with the opposite end of said passage, the forward end of said tube being tapered and the opening in the tube terminating upon the tapered surface, and a nozzle surrounding said tube and controlling the discharge of paint therefrom, said nozzle having a screw thread connection with said sleeve.
